UNITED STATES PATENT OFFICE.

HENRY H. ALTHOFF, OF NEW YORK, N. Y.

BURIAL VAULT.

Application filed December 21, 1923. Serial No. 682,020.

To all whom it may concern:

Be it known that I, HENRY H. ALTHOFF, a citizen of the United States, and a resident of the city of New York, Middle Village, borough of Queens, in the county of Queens and State of New York, have invented a new and Improved Burial Vault, of which the following is a full, clear, and exact description.

This invention relates to a new and improved subterraneous vault for burial purposes wherein one or a comparatively large number of bodies may be placed and protected against vermin and seepage.

An object of the invention is to provide an improved structure or vault which is simple in its form but which produces substantially an air tight structure whereby the bodies in the vault are protected against the action of the elements.

Another object of the invention is to provide a grave vault in which a plurality of bodies may be placed but so constructed that no part of the vault will be seen above the ground except the usual covering slab of marble or other desired material.

A still further object, more specifically, is to provide a burial vault in which the enclosing structure is substantially water and air tight and in which a drain is provided for any condensation of vapor in the vault.

In the accompanying drawing—

Figure 1 is a longitudinal vertical sectional view through a burial vault disclosing an embodiment of the invention;

Fig. 2 is an enlarged fragmentary perspective view of part of the upper projecting railing of the vault disclosing certain features of the invention;

Fig. 3 is a view similar to Fig. 2 but showing part of the cover in place; and

Fig. 4 is a sectional view through the vault shown in Fig. 1, taken approximately on line 4—4 of Fig. 1.

Referring to the accompanying drawing by numerals, 1 indicates the bottom of the vault, which is preferably made of concrete, said bottom being integral with the various side walls 2 which merge into and are integral with the top 3. As indicated in Figs. 1 and 4, the top 3 is provided with an upwardly extending member 4 which acts, in a certain sense, as a collar or neck and projects from the top 3 to the surface of the ground, where it is reduced and forms an annular flange member 5, which flange is

provided with a groove 6. The groove 6 is adapted to receive a soft filling member 7 which may be a solid rod or a tube formed of comparatively soft metal, as, for instance, lead, so that when the cover 8 is placed in position the weight will compress the filling member or sealing member 7, as shown in Fig. 3. The cover 8 is provided with a groove 7 whereby the outer part of the cover 6 will extend below the flange 5 and hide the same from view. It will be noted that the top 3 is an appreciable distance below the surface of the ground and is preferably arranged at a convenient angle so that any surface water passing down through the earth 10 will readily flow off the top and into the soil at the sides of the vault. The entire vault, except where the cover 8 fits, is enclosed in a waterproof structure 11, which may be any desired material, as, for instance, three-ply or waterproof felt. On the top 3, in addition to this waterproof material, is provided a covering 12 of copper sheeting which extends down over the corners 13 and also upwardly to form part of the upper edge of the member 4.

From Fig. 1 it will be noted that the upper edge of the member 4 is slightly below the surface of the ground 10, consequently, the lower edge of the cover 8 may extend a short distance below the ground 10 to give a pleasing appearance and to prevent any one from seeing any part of the vault except the cover 8. The top 3, and also the other parts, may be reenforced by beams and fire reenforcing members, as preferred.

It is also evident that the vault might be made as large as desired, and, in the manufacture, shelves or floors 14 are preferably cast integral with the side walls 2, and of a proper width to receive one or more bodies, as preferred. Each of the crypts 15 are also preferably provided with a removable door 16 held in place in any desired manner, as, for instance, by sealing means around the edges or merely by suitable fastening screws or pins 17.

The opening 18 through which the bodies are lowered into the vault is of a desired width and that same width is reserved as a vertical passageway or hole down to the bottom 1 and, in fact, extends into the bottom 1 for forming a depressed portion 19. This portion is provided with an inclined bottom, inclined toward the drain pipe 20,

which drain pipe is preferably provided with a strainer 21 which discharges into a somewhat inverted container 22 supplied with a small amount of gravel or other 5 rough material 23.

As the vault is waterproof and substantially air-proof no water or other liquid can enter unless it should rain while the cover 8 is removed; this very seldom occurs, 10 but it has been found that moisture gathers on the walls of the passageway 18 and drops to the bottom, said moisture resulting from condensation and probably from causes unknown. In order that the vault may remain 15 comparatively dry, the drain pipe 20 and associated parts are provided to remove this condensation. As the vault is substantially air tight, it has been found that there is no backward seepage through pipe 20 and 20 the vault is maintained in a comparatively dry state continually. It will be noted that 25 the sealing member 7 presents what may be termed a temporary seal, which will maintain the vault tight continually but permit ready removal of the cover in case it should be desired to place a new body in the vault at any time. It is, of course, 30 evident that when the vault is completely filled a permanent sealing material could be applied, though ordinarily the lead or other sealing member 7 would prevent an effective sealing as necessary.

What I claim is:—

1. A burial vault, comprising a bottom, 35 side walls, end walls and a top merging into the side and end walls, said top in turn merging into a forwardly extending collar having a projecting flange, a cover resting on said flange, and collapsible sealing means arranged between the cover and flange.

2. In a burial vault, a top member having an opening, said top member being inclined on its upper surface and adapted to 45 be spaced below the surface of the ground, said top member having a neck around said

opening projecting to a point near the surface of the ground, a waterproof structure arranged separately but in contact with the bottom, side walls, end walls and top of 50 the vault, a sheet-metal covering for said top and for the sides of said neck, and a cover plate for covering the opening of said top.

3. In a vault of the character described, 55 a vault body formed with a top having an opening and a shoulder surrounding the opening, part of said shoulder being provided with a groove extending entirely around the opening, a hollow soft-metal 60 member arranged in said groove and projecting therefrom, and a cover adapted to rest on said soft-metal member, said cover being sufficiently heavy to collapse, to a certain extent, said metal whereby a substantially air-tight seal is produced.

4. In a burial vault, a body provided with an opening at the top, said body having an annular projecting member surrounding said opening and provided with a groove 70 in its upper surface, a lead pipe arranged in said groove and projecting upwardly therefrom, and a cover plate having a groove in its lower surface adapted to receive said upwardly extending portion and said lead pipe, said cover being of sufficient weight 75 to collapse the lead pipe and produce a substantially air-tight connection.

5. A burial vault, comprising a bottom, 80 side walls, end walls and a converging top open in the center, said top having an upstanding flange, said flange at its upper edge being substantially in the same plane as the earth in which the vault is located while said converging top is appreciably above the level of the earth whereby a very restricted structure is presented to view, a cover resting on said flange, and means arranged on top of said flange engaged by said cover for sealing the cover.

HENRY H. ALTHOFF
